LOCK

John A. Connell, Carlsbad, N. Mex.

Application July 29, 1944, Serial No. 547,180

6 Claims. (Cl. 70—383)

1

This invention relates to improvements in pin-tumbler locks, and more particularly to improvements in locks of this type in which the stationary case or cylinder is provided with a plurality of series of driver pins, and the revolving tumbler-carrier or core has a single series of pins to cooperate therewith.

One of the objects of the invention is to supply a lock of this character in which an authorized person, such as the manager of a hotel or office building, for example, may change the combination of the lock simply by the use of keys, so that a person possessing a key which has normally opened the lock, may insert his key, after the combination is changed, but will be unable to thereby turn the revolving core which controls the bolt.

Another object of the invention is to furnish a lock having such characteristics and provided with means for preventing others than the manager of the hotel or office building from withdrawing a key except when the revolving core is in a predetermined position. By such means, the tenant will be frustrated from changing the combination by the use of a key similar to his individual one.

Another object is to provide improved means for lubricating locks, such means including a lubricant chamber adapted to contain powdered graphite, for example, from which the lubricant is discharged by the action of the driver pins, so that the lubricant will be fed each time a key is inserted and removed, or reciprocated back and forth in the keyway. The lubricating means is claimed in a divisional application, Ser. No. 604,833, filed July 13, 1945, which is now Patent No. 2,422,224, dated June 17, 1947.

With the foregoing objects outlined and with other objects in view which will appear as the description proceeds, the invention consists in the novel features hereinafter described in detail, illustrated in the accompanying drawings, and more particularly pointed out in the appended claims.

In the drawings—

Fig. 1 is a front elevation of a lock in accordance with the invention.

Fig. 2 is a side elevation of the same.

Fig. 3 is a rear elevation.

Fig. 4 is a plan view of one of the tenant's keys.

Fig. 5 is a similar view of one of the manager's keys corresponding to that tenant's key.

Fig. 6 is a front elevation of a modified form of the lock, partly broken away, to illustrate a

2

portion of the means employed to prevent the tenant from withdrawing his key except when the revolving core is in a certain position.

Fig. 7 is a plan view of a tenant's key of the type to be used with the lock shown in Fig. 6.

Fig. 8 is a similar view of a manager's key to be used with the lock shown in Fig. 6.

Fig. 9 is a longitudinal vertical sectional view on the line 9—9 of Fig. 1, with the key removed.

Fig. 10 is a similar view after a tenant's key has been inserted.

Fig. 11 is a longitudinal sectional view on the line 11—11 of Fig. 1, after the revolving core has been turned to bring the keyway into alignment with said line.

Fig. 12 is a view similar to Fig. 11, but showing one of the manager's keys in place of the tenant's key.

Fig. 13 is a transverse vertical sectional view taken on the line 13—13 of Fig. 12.

Fig. 14 is a view similar to Fig. 13, but showing the revolving core in its normal position.

Referring to the drawings, 15 designates a stationary case or cylinder provided with a bore 16 extending lengthwise thereof below its center, for the reception of a rotatable core 17 having an abutment flange 18 at the front of the lock and provided at its rear with a conventional bolt actuating member 19. As usual, the core

30 is provided with a keyway or slot 20 communicating with a series of radially disposed holes 21 extending lengthwise thereof, for the reception of reciprocating pins 22, which cooperate with driving pins 23 arranged in a series of holes 24 disposed in a line extending lengthwise of the cylinder or case 15. As is customary, the drivers 23 are yieldingly urged toward the core by means of coil springs 25 positioned in the holes 24 and held in place by a slidable plate 26 which fits in a

35 groove 27 extending lengthwise of the periphery of the case.

In accordance with my invention, I arrange changeover elements or disks 28, 29, 30, 31, and 32 between the pins 22 and the drivers 23, except between the last driver 23a of the series and the pin with which it cooperates.

In the cylinder or casing of such a lock, I place one or more additional series of holes 33, 34 for the reception of one or more additional sets of drivers 35, 36, but in the form of the invention shown in Figs. 1, 2, 3, and 9 to 14, inclusive, it will be noted (Figs. 11 and 12) that the holes 33, 34 are less in number than the pin holes 21 of the rotatable core. This is for the purpose

40 of preventing withdrawal of the tenant's key ex-

45 cept between the last driver 23a of the series and the pin with which it cooperates.

In the cylinder or casing of such a lock, I place one or more additional series of holes 33, 34 for the reception of one or more additional sets of drivers 35, 36, but in the form of the invention shown in Figs. 1, 2, 3, and 9 to 14, inclusive, it will be noted (Figs. 11 and 12) that the holes 33, 34 are less in number than the pin holes 21 of the rotatable core. This is for the purpose

50 of preventing withdrawal of the tenant's key ex-

55 cept between the last driver 23a of the series and the pin with which it cooperates.

cept when the keyway 20 is in the same plane as the holes 24.

Referring now to Fig. 9, it will be noted that with the key out of the slot, drivers 23, 23a normally extend across the junction between the periphery of the core 17 and the surface of the bore 16, so that the core cannot be turned. If, however, the tenant inserts his key 37 (Fig. 10), the serrated edge 38 thereof will lift the pins 22 and disks 28—32 into a position to allow the core to be turned by the key for actuating the bolt-operating member 19. However, whenever the rearmost pin 22, which is carried by the core moves to one side or the other of the line of holes 24, it confronts a solid portion of the case or cylinder, as indicated at 39 in Fig. 11. Therefore, the tenant's key cannot be withdrawn, because the hump 40 at the inner end thereof is interlocked with the rearmost pin 22 of the core. Of course, it can be withdrawn whenever the keyway is aligned with the holes 24.

We will now assume that the manager, for one reason or another, desires to alter the lock in such a way that the tenant, although he may insert his key, cannot turn the core. Under such circumstances, the manager when the core is in the position shown in Figs. 1 and 3, inserts his first key 41 (Fig. 5) which corresponds with the tenant's key 37, except that the hump 40 is omitted, and a nose 42 is provided to raise the rearmost pin 22 of the core. Hence, when the manager inserts key 41, it will bring the parts into the position shown in Fig. 10. At this time, the core may be turned to bring the keyway into alignment with the holes 33. When this position is reached, the manager withdraws his key 41 and such withdrawal is not interfered with, because the rearmost pin 22 of the core is not interlocked with this key. After such withdrawal, the manager inserts his second key 43 (Fig. 8) which key, let us say, has a notch 44 for the front pin 22 of the core which is not as deep as the notch 46 of the tenant's key 37 (Fig. 10) or the notch 45 of the first key of the manager (Fig. 5). Hence, upon the insertion of the key 43 (Fig. 12) the notch 44 will raise the front pin of the core to a higher elevation than the other keys so as to project the corresponding disk 28 into the front hole 33 of the case 15. He then turns the key in a counter-clockwise direction to return the keyway to the vertical position where it is in alignment with the holes 24. He then withdraws the key 43. Now, if the tenant attempts to open the lock by means of the key 37, it will be clear that the front pin 22 of the core will drop into the notch 46, and as there is no disk 28 between this pin and its complementary driver 23, the latter will not be lifted to as great a height, but will obstruct the junction between the rotatable core and the case. Therefore, the tenant is prevented from opening the lock. Of course, the manager can readily open it by first using the key 43 to shift the keyway into alignment with the holes 33 before withdrawing this key and inserting his key 41 to effect the transfer of the disk 28 back into the front hole 21 of the core. Then, this key may be turned in a counter-clockwise direction to bring the keyway back into alignment with the holes 24 before the key 41 is withdrawn.

It will be obvious that by varying the lengths of the pins 22, the drivers 23, or the thicknesses of the disks 28—32, and changing the profiles of the keys accordingly, numberless combinations may be obtained. Furthermore, a greater variety

may be achieved by the employment of the second set of holes 34 and the drivers 36.

Instead of employing a hump 40 at an end of a key to prevent withdrawal of the key except when the latter is in a particular position, I can use the structure illustrated in Figs. 6 and 7. In this embodiment, the cylinder 15a has secured to the front end thereof, a plate 48 provided at its rear with a circular rabbet or recess 49 communicating with an entrance notch 50. When a tenant's key 51 (Fig. 7) having a lug 52 thereon is inserted in such a lock, the lug 52 will move through the notch 50, and then if the key is turned, the lock will enter the recess or groove 49 so that the key cannot be withdrawn except when it is in a special position.

In the drawings, I have shown a lubricating means which may be used with various types of locks, especially those having two or more sets of driver pins in the case. In accordance with the invention one or more holes 53 and 54 are formed in the lock casing and each hole is connected by a passageway 54' with each of the driver pin holes 24. Each hole 53, 54, also, communicates with the driver pin holes 33, 34 by means of ducts 55. The holes or chambers 53, 54 are preferably charged with a powdered lubricant, such as graphite and, of course, the holes will be closed by any suitable means, such as removable plugs 56, Fig. 3, to permit recharging the same. With lubricant in the chambers 53, 54, it will be obvious that whenever the drivers 23 are reciprocated by the ordinary insertion and removal of the key, the drivers will act as pistons to feed the lubricant into the holes 24, 33, and 34, from which the lubricant will travel to the rotatable core and to the pin holes 21. For more positive lubrication, one may use either of the manager's keys 41, 43, for example, when the pin holes 21 are aligned with either series of holes 33 or 34, and by moving the key back and forth several times can cause feeding of the lubricant.

From the foregoing, it is believed the construction, operation and advantages of my invention may be readily understood by those skilled in the art, and it is manifest that changes may be made in the details disclosed without departing from the spirit of the invention, as expressed in the claims.

What I claim and desire to secure by Letters Patent is:

1. In a pin tumbler lock, a stationary cylinder, a core rotatably mounted in the cylinder and provided with a keyway, a set of reciprocating pins slidably mounted in the core and extending into the keyway, the cylinder being provided with at least two lengthwise series of holes, a set of drivers in each series of holes, said pins being adapted to coincide with either series of holes in the cylinder by the revolution of the core, a change-over element normally arranged in the core at the end of one of the pins, a key insertable into the keyway and cooperable with the pins when they register with the first series of holes of the cylinder for shifting the first set of drivers and the change-over element into a position where they will not interfere with the turning of the core in the cylinder until the pins register with the second series of holes, a second key adapted to be inserted in the keyway while the pins register with the first series of holes for shifting the first set of drivers and the change-over element into a position where they will not interfere with the turning of the core in the cylinder until the pins register with the second series of holes, a

third key adapted to be inserted in the keyway while the pins register with the second series of holes for moving the pins and for shifting the change-over element into one of the holes of the second series to permit the third key to return the core to its first position after transferring the change-over element from the core of the cylinder whereby the first key is then prevented from shifting the pin which cooperated with the change-over element to a position where it will release the core from the cylinder, and means to prevent the first key from being withdrawn from the keyway when the reciprocating pins of the core register with the second series of holes of the cylinder, the second and third keys being so shaped that they are free of said means and either may be removed from the keyway while the reciprocating pins of the core are in registration with the second series of holes of the cylinder.

2. In a pin tumbler lock, a stationary cylinder, a core rotatably mounted in the cylinder and provided with a keyway, a set of reciprocating pins slidably mounted in the core and extending into the keyway, the cylinder being provided with at least two lengthwise series of holes, a set of drivers in each series of holes, said pins being adapted to coincide with either series of holes in the cylinder by the revolution of the core, a change-over element movable from the core to the cylinder and vice versa, said element being normally arranged between one of the drivers and one of the pins, a first key insertable into the keyway and cooperable with the pins when they register with the first series of holes of the cylinder for shifting the first set of drivers and the change-over element into a position where they will not interfere with the turning of the core in the cylinder until the pins register with the second series of holes, means to prevent the first key from being withdrawn from the keyway when the reciprocating pins of the core register with the second series of holes of the cylinder, means cooperating with the pins while the first key is removed from the keyway for shifting the core from the first series of holes to bring the pins into registry with the second series of holes, and a second key adapted to be inserted in the keyway while the pins register with the second series of holes for moving the pins and for shifting the change-over element into one of the holes of the second series to permit the second key to return the core to its first position after transferring the change-over element from the core to the cylinder whereby the first key is then prevented from shifting the pin which cooperated with the change-over element to a position where it will release the core from the cylinder, the second key being so shaped that it is free of said means and may be removed from the keyway while the reciprocating pins of the core are in registration with the second series of holes of the cylinder.

3. A pin tumbler lock as claimed in claim 2, in which said means comprises an extra reciprocating pin arranged in the core at one end of the set of reciprocating pins, and means in the cylinder to prevent said extra pin from moving outwardly toward the cylinder when the pins register with the second series of holes in the cylinder.

4. In a pin tumbler lock, a stationary cylinder, a cylindrical core rotatably mounted in the cylinder and provided with a keyway, a set of reciprocating pins slidably mounted in the core and extending into the keyway, the cylinder being provided with first and second series of holes substantially radially arranged with reference to

the core, a set of drivers slidably arranged in each series of holes, said pins being adapted to axially coincide with either series of holes in the cylinder by the revolution of the core and one set of drivers being the only means normally preventing rotation of the core by a key from the position where the reciprocating pins register with the first series of holes of the cylinder to a position where the pins register with the second series of holes, a change-over element normally arranged in the core at the end of one of the pins, a first key insertable into the keyway and cooperable with the pins when they register with the first series of holes of the cylinder for shifting the first set of drivers and the change-over element into a position where they will not interfere with the turning of the core in the cylinder until the pins register with the second series of holes, means to prevent the first key from being withdrawn from the keyway when the reciprocating pins of the core register with the second series of holes of the cylinder, means cooperating with the pins while the first key is removed from the keyway for shifting the core to bring the pins into registry with the second series of holes, and a second key adapted to be inserted in the keyway while the pins register with the second series of holes for moving the pins and for shifting the change-over element into one of the holes of the second series to permit the second key to return the core to its first position after transferring the change-over element from the core to the cylinder whereby the first key is then prevented from shifting the pin which cooperated with the change-over element to a position where it will release the core from the cylinder, the second key being so shaped that it is free of said means and may be removed from the keyway while the reciprocating pins of the core are in registration with the second series of holes of the cylinder.

5. In a pin tumbler lock, a stationary cylinder, a core rotatably mounted in the cylinder and provided with a keyway, a set of reciprocating pins slidably mounted in the core and extending into the keyway, the cylinder being provided with at least two lengthwise series of holes spaced from one another circumferentially of the core, a set of drivers in each series of holes, said pins being adapted to coincide with either series of holes in the cylinder by the revolution of the core, a change-over element normally arranged in the core at the end of one of the pins, a key insertable into the keyway and cooperable with the pins when they register with the first series of holes of the cylinder for shifting the first set of drivers and the change-over element into a position where they will not interfere with the turning of the core in the cylinder until the pins register with the second series of holes, means to prevent the first key from being withdrawn from the keyway when the pins of the core register with the second series of holes of the cylinder, means cooperating with the pins while the first key is removed from the keyway for shifting the core to bring the pins into registry with said second series of holes, and a second key adapted to be inserted in the keyway while the pins register with the second series of holes for shifting the pins and for shifting the change-over element into one of the holes of the second series to permit the second key to return the core to its first position after transferring the change-over element from the core to the cylinder whereby the first-mentioned key is then prevented from shifting the pin which cooperated with the change-over element to a

position where it will release the core from the cylinder, the second key being so shaped that it is free of said means and may be removed from the keyway while the reciprocating pins of the core are in registration with the second series of holes of the cylinder.

6. In a pin tumbler lock, a cylinder having a first set of holes, a set of drivers slideable in said holes, a core rotatable in said cylinder and having a keyway and a second set of holes registering with the first set in one angular position of said core, pins slideable in the second set of holes, a change-over element arranged in one of the second set of holes at the outer end of one of said pins, said cylinder having a third set of holes registering with the second set when the core is turned to a second angular position, drivers slideable in the third set of holes, a key insertable in the keyway when the core is in the first angular position to shift the pins to release the core for rotation, retaining means effective with respect to said key to prevent it from being withdrawn from the keyway when the core is in the second angular position, means cooperating with the pins while said key is removed from the keyway for shifting the core to bring the pins into registry

with the third set of holes, and a second key insertable in the keyway when the core is in the second angular position and operable to shift the change-over element and operating the pins to release the core with the element in the shifted position within one of the holes of the third set, the second key being so shaped that it is free of said means and may be removed from the keyway while the reciprocating pins of the core are in registration with said third set of holes.
